(57) **ABSTRACT**

A new variety of *Bidens* plant named 'KLEBF11764' particularly characterized by early and rich flowering with inflorescences situated above the plant center and short peduncles is disclosed.

1 Drawing Sheet

2

shown are as true as can be reasonably obtained by conventional photographic procedures. The photograph was taken on a plant about 3 months old grown from rooted cuttings in a 10 centimeter pot in a glass greenhouse in Stuttgart, Germany under normal horticultural practices.

DESCRIPTION OF THE NEW VARIETY

The following detailed descriptions set forth the distinctive characteristics of 'KLEBF11764'. The data which define these characteristics were collected from asexual reproductions carried out in Stuttgart, Germany. The plant history was taken in spring 2011 on 10 week old plants grown in 10 centimeter pots in a glass greenhouse with a minimum pinch date of 9 weeks. The color readings were determined under natural light. Color references are to The R.H.S. Colour Chart of The Royal Horticultural Society of London (R.H.S.), Fifth Edition (2007).

DESCRIPTION OF THE NEW PLANT

Classification:

Family.—Asteraceae.

Genus and species.—*Bidens ferulifolia*.

Common names.—*Bidens*, Beggarticks, Bur-marigold, tickseed.

Denomination.—'KLEBF11764'.

Parentage:

Female parent.—*Bidens* plant 'BF 07 0011'.

Male parent.—Unknown.

Plant:

Propagation.—Vegetative cuttings.

Time to initiate and develop roots.—2 weeks.

Root description.—Fine white roots, RHS N155C.

Rooting habit.—Freely branching.

SUMMARY OF THE INVENTION

The following are the most outstanding and distinguishing characteristics of this new variety when grown under normal horticultural practices in a glass greenhouse in Stuttgart, Germany.

1. Early and richly flowering;
2. Flowers situated above the plant centers; and
3. Short peduncles.

DESCRIPTION OF THE PHOTOGRAPH

This new *Bidens* plant is illustrated by the accompanying photograph which shows flowers of the plant. The colors

COMPARISON WITH PARENTAL AND COMMERCIAL VARIETIES

⁴³ ‘KLEBF11764’ differs from the female parent, *Bidens* plant ‘BF 07 0011’ (unpatented), in that ‘KLEBF11764’ is a richer flowering variety and has shorter peduncles.

‘KLEBF11764’ differs from commercial variety ‘KLEBF07003’ (U.S. Plant Pat. No. 20,533) in that ‘KLEBF11764’ has an upright/semi-trailing habit, whereas ‘KLEBF07003’ has a trailing habit. In addition, ‘KLEBF11764’ initiates and develops roots in 2 weeks, whereas ‘KLEBF07003’ initiates and develops roots in 3 weeks.

We claim:

1. A new and distinct variety of *Bidens* plant named 'KLEBF11764' as shown and described herein.
